UNITED STATES PATENT OFFICE.

FREDRIK LJUNGSTRÖM, OF BREVIK, LIDINGÖN, SWEDEN, ASSIGNOR TO AKTIEBOLAGET LJUNGSTRÖMS ANGTURBIN, OF STOCKHOLM, SWEDEN, A CORPORATION.

ARRANGEMENT FOR FORCED LUBRICATION FOR LOCOMOTIVES AND SIMILAR VEHICLES.

1,368,948.

Specification of Letters Patent. Patented Feb. 15, 1921.

Application filed February 2, 1920. Serial No. 355,639.

To all whom it may concern:

Be it known that I, FREDRIK LJUNGSTRÖM, chief engineer, subject of the King of Sweden, residing at Brevik, Lidingön, Sweden, have invented certain new and useful Improvements in Arrangement for Forced Lubrication for Locomotives and Similar Vehicles of which the following is a specification.

10 The present invention relates to an arrangement for forced lubrication for locomotives and similar vehicles, and has for its purpose to provide for a suitable and abundant lubrication.

15 The invention consists in the provision of at least two collecting troughs situated preferably right above the rails, the oil flowing from the various machine parts being received by and collected in the said

20 troughs. These troughs communicate with casings surrounding the machine parts.

Further, the invention consists in the collecting troughs being connected with two suction pumps mounted apart from each 25 other, which pumps convey the oil to receptacles situated higher up. Preferably, these suction pumps are arranged on the same shaft as the force pumps used to pump the oil from the oil receptacle to the places of

30 lubrication.

The suction pumps preferably are dimensioned so that they each take more than half the quantity of oil.

The invention, moreover, consists in part 35 of the oil in the casing or oil receptacle surrounding the connecting rods being thrown against the walls of the casing in such manner that the casing will serve as an oil cooler; and, furthermore, the invention as 40 applied to an oil box attached to the frame of the vehicle consists in the packing around the wheel- or crank shaft being effected by screens of sheet metal or the like attached to the shaft or the bearings thereof, and 45 sliding in contact with the side of the oil box.

The accompanying drawings illustrate by way of example a few embodiments of the invention as applied to an engine car with 50 power transmission effected by means of connecting or coupling rods.

Figures 1 and 2 show one embodiment in elevation and in end view respectively, Fig.

1 being a section taken on line A—A in Fig. 2, and Fig. 2 a section taken on line 55 B—B in Fig. 1. Fig. 3 is a part of Fig. 2 drawn to a larger scale, and Fig. 4 is an enlarged view of an embodiment of the packing between the casing and the shaft. Fig. 5 is a longitudinal section of an embodiment of the arrangement disclosed in Fig. 1, and Fig. 6 shows a detail of Fig. 5 drawn to a larger scale.

In Figs. 1 and 2, 1 denotes the casing or oil box surrounding the crank, the connecting rods and the coupling rods 3, the said casing being attached to the frame 2. In this embodiment, the casing 1 is so united with the frame that the latter forms the inner side of the oil box. Arranged at the 70 bottom of the oil box are the collecting troughs 4.

Owing to the resiliency of the vehicle, there will be movements, in operation, of the shaft relatively to the frame 2 and the 75 oil box 1, which necessitates the application of a packing around the said shaft.

The oil, which in operation is thrown against the walls of the casing or oil box 1, flows down the walls to the collecting 80 troughs, whereby it is being cooled.

Fig. 3 shows an embodiment of such a packing as applied to an arrangement according to Figs. 1 and 2. Attached to the wheel shaft 8 or preferably to the bearings 85 6 thereof is a sliding screen 7 bearing against the side of the box 1, that is to say against the frame 2. The screen slides in steady contact with the frame through the resiliency thereof and forms a tight packing 90 at all positions of the shaft 8 with respect to the box 1. In the present case, the box 1 is provided with a narrow part 5 holding the collecting troughs at the bottom thereof.

Fig. 4 shows a further embodiment of the above-mentioned packing and another way of attaching the oil box 1 to the frame. In this case, the oil box 1 is attached with its inner side 9 to the frame 2. The disk 100 7 situated on the bearing 6 now also bears against the side of the box 1, this, however, being effected in the present case through the medium of an additional disk or ring 10 fastened to the oil box 1, which disk or 105 ring provides for two contact surfaces,

whereby the tightness of the packing is increased. The ring 10 is of a U-shaped cross section.

Figs. 5 and 6 show a further embodiment 5 of the invention with a collecting trough 4 disposed right above the rail 12. In this case the collecting trough not only communicates with the oil box 1 around the cranks and the connecting rods 3, but also with the casing 10 14 (Fig. 6), which surrounds the remaining machine parts. In this case, too, there are two collecting troughs, one above each rail. 11 designates the suction pipe conveying the oil from the collecting troughs.

15 To convey the oil from these collecting troughs there is arranged a pump for each trough. Fig. 5 shows these pumps connected to the same shaft 16 as the force oil pumps. The pumps are arranged in the pump casing 20 15. The shaft 16 receives its motion for instance from a shaft in the gearing 17. The suction pumps draw up the oil from the collecting troughs 4 and convey it through the pipes 11 to the oil receptacle 19. The force pumps, on the other hand, press the oil from 25 the receptacle 19 to the various places of lubrication 20 through the pipes 21.

Owing to the limited space within the load profile, difficulties have always been met 30 with in constructing suitable contrivances to collect the waste oil in locomotives. According to the present invention, however, it has been made possible to employ collecting troughs for the oil, forced lubrication without any losses of oil to speak of having also 35 been facilitated by the invention.

What I claim as new and desire to secure by Letters Patent of the United States is:—

1. The combination with a locomotive having a number of movable parts and 40 wheels, of a plurality of collecting troughs arranged in close proximity to the wheels and disposed above the rails on which the wheels travel, casings surrounding the movable parts, means for gathering lubricant 45 from the casings and for conveying the same to said troughs, a plurality of independent suction pumps arranged to gather the lubricant deposited in said troughs, and receptacles situated above said casings and connected to the discharge members of the pumps 50 for receiving the lubricant gathered from the troughs.

2. A combination as defined in claim 1 in which certain of the movable parts include 55 cranks and coupling rods and in which one of the casings surrounds said cranks and coupling rods and has a wall against which the lubricant is thrown by said cranks and coupling rods for the purpose of cooling the 60 lubricant.

3. A combination as defined in claim 1 in which one of the movable parts is mounted 65 in a bearing, and a sliding disk carried by said bearing and slidably engaging one of said casings.

In testimony whereof I affix my signature in presence of two witnesses.

FREDRIK LJUNGSTRÖM.
